UNITED STATES PATENT OFFICE.

ANNA NESS, OF FULTON, SOUTH DAKOTA.

DESIGN FOR A SEWING-RACK.

44,538.

Specification for Design.

Patented Aug. 19, 1913.

Application filed June 14, 1913. Serial No. 773,767. Term of patent 3½ years.

To all whom it may concern:

Be it known that I, ANNA NESS, a citizen of the United States, and resident of Fulton, in the county of Hanson and State of South Dakota, have invented a new, original, and ornamental Design for Sewing-Racks, of which the following is a specification, reference being had to the accompanying drawing, forming part thereof.

The figure is a perspective view of a sewing rack showing my new design.

I claim:

The ornamental design for a sewing rack, as shown.

ANNA NESS.

Witnesses:

A. T. MINEHART,
HARRY C. NESS.
